UNITED STATES PATENT OFFICE

92,705

DESIGN FOR A COMBINED PENCIL AND ADVERTISING DEVICE

Frank C. Deli, Chicago, Ill., assignor to Autopoint
Company, Chicago, Ill., a corporation of Illinois

Application January 8, 1934, Serial No. 50,350

Term of patent 3½ years

To all whom it may concern:

Be it known that I, FRANK C. DELI, a citizen of the United States, residing at Chicago, in the county of Cook and State of Illinois, have invented a new, original, and ornamental Design for a Combined Pencil and Advertising Device, of which the following is a specification, reference being had to the accompanying drawing, forming part thereof.

Fig. 1 is a side view of a combined pencil and advertising device showing my new design;

Fig. 2 is a similar view taken at right angles to Fig. 1; and

Fig. 3 is an end view.

I claim:

The ornamental design for a combined pencil and advertising device, as shown.

FRANK C. DELI.
